ERASER ATTACHMENT FOR TYPEWRITERS

George H. Huiaff, Jr., Wilmington, N. C.

Application June 18, 1938, Serial No. 214,561

1 Claim. (Cl. 248—226)

My invention relates to new and useful improvements in an eraser attachment for typewriters and has for its principal object the provision of novel means for supporting and operating the eraser, the eraser being in the form of a disc adapted to be swung or moved into engagement with the paper surrounding the typewriter platen and rotated to make the desired erasures.

Another object of the invention consists in the provision of novel forms of brackets adapted to be detachably connected to a typewriter, the brackets having bearing portions for rotatably supporting a shaft which carries the eraser, the shaft being rotated in a novel manner to bring the eraser into engagement with the paper surrounding the typewriter platen or raised out of engagement therefrom.

A further object of the invention resides in the provision of novel means for normally holding the eraser in raised position but permitting the same to be lowered into operative position relative to the typewriter platen to permit erasing, means also being provided for rotating the eraser while in contact with the paper around the platen and on which the letters or words have been typed.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claim.

In the drawings—

Fig. 1 is a top plan, a portion of the typewriter keyboard being broken away.

Fig. 2 is a fragmental top plan showing the eraser in raised position.

Fig. 3 is an end view, with the typewriter platen shown in section, showing the eraser in raised position.

Fig. 4 is a view similar to Fig. 2 showing the eraser in lowered position.

Fig. 5 is a view similar to Fig. 3 showing the eraser in lowered position.

Fig. 6 is a fragmental rear elevation with parts shown broken away.

Fig. 7 is a horizontal section on the line 7—7 of Fig. 3 looking in the direction of the arrows.

Fig. 8 is a section on the line 8—8 of Fig. 5 looking in the direction of the arrows; and

Fig. 9 is a section on the line 9—9 of Fig. 5 looking in the direction of the arrows.

As the typewriter proper forms no part of the present invention no detailed description thereof will be given other than to say that 1 indicates a portion of the typewriter frame, 2 a portion of the keyboard, 3 the ordinary platen and 4 the knobs secured to each end of the platen for rotating the same in the usual well-known manner.

At 5 and 6 I have illustrated brackets or plates adapted to be detachably connected to opposite end portions of the typewriter frame, each of these brackets or plates being formed at its upper end with a rearwardly directed extension 7 by 15 and between which is rotatably supported a hollow shaft or sleeve 7' to which is secured a housing 8 which supports and carries the rotatable eraser disc 9. The eraser disc is adapted to be rotated through suitable mechanism which is 20 mounted within the housing 8 and a shaft which extends through the hollow shaft or sleeve 7' and which in turn is operated through means of the knob 10. As the eraser support and rotating means for the eraser form no part of the present invention a further detailed description will not 25 be given but reference is made, for an understanding of said mechanism, to applicant's co-pending application filed January 28, 1938, Serial No. 187,520.

Each of the brackets or plates 5 and 6 has 30 detachably connected to its inner face, by means of the screws 11 or other suitable fastenings, a plate 12 having an edge portion turned at right angles, as shown at 13, which right angle portion 35 is formed at its end with an inwardly directed extension 14, as shown more particularly in Fig. 8 of the drawings. The plates 12 are positioned intermediate the ends of the brackets or plates 5 and 6, as shown more particularly in Figs. 3, 5 and 6 of the drawings and are adapted to be engaged with a vertical edge portion of an end of the frame 1 as clearly shown. A screw 15 is received in a threaded opening in the brackets or plates 5 and 6 and associated plate 12 and is 40 adapted for adjustment to secure the brackets or plates 5 and 6 to the frame 1 as will presently be brought out more in detail.

Secured to the bottom edge of each of the brackets or plates 5 and 6, by means of the screws 50 16 or other suitable fastenings, is a plate 17 having a bottom extension 18 provided at its outer edge with an upwardly directed portion or flange 19 providing a channel to receive a bottom edge of the typewriter frame 1 as shown more particularly in Fig. 9 of the drawings. Screws 20 are

received in threaded openings in the plates 17 and extend through threaded openings in the brackets 5 and 6 to engage with the outer face of the edge of the typewriter frame for securing the brackets in position.

From what has been said it will be seen that the brackets or plates 5 and 6 which support the eraser, and operating means therefor, may be easily connected to or disconnected from the typewriter frame and are adapted for use on typewriters of various makes. As has been described, and as is shown, when the brackets or plates 5 and 6 are in position the extensions 13 and 14, of the plates 12, engage around an edge portion of the rear of the frame whereas the channels formed in the plates 17 engage under and around a bottom edge of the typewriter frame. By adjusting the screws 15 and 20 they engage the faces of the typewriter frame, as shown more particularly in Figs. 8 and 9 of the drawings, and force the portions 14 of the plates 12 and the portions 19 of the plates 17 into tight frictional engagement with an opposite face of the frame and therefore securely hold the brackets or plates 5 and 6 in position. The brackets or plates 5 and 6 may be easily removed by releasing the screws 15 and 20. At times, due to parts of the typewriter, it may be impossible to remove the brackets or plates 5 and 6 by merely loosening the screws 15 and 20, but if this is the case the plates 12 may be removed by releasing the screws 11 and the plates 17 may be removed by releasing the screws 16. It is thought that this will be clearly understood from an examination of the drawings.

In Figs. 1, 2 and 3 of the drawings I have shown the eraser or eraser disc in its normal raised position. When it is desired to erase the eraser disc is to be swung down into the position shown in Figs. 4 and 5 of the drawings. In order to raise and lower the eraser, into the desired positions, I have provided the novel mechanism which I will now describe, it being understood that when the eraser or eraser disc is in its lowermost position, shown in Figs. 4 and 5 of the drawings, in engagement with the paper which is around the platen, it may be rotated in the manner, and through the mechanism, described and illustrated in my co-pending application above identified.

A collar 21 is secured to or formed as a part of the hollow shaft 1' and formed as a part of this collar, or secured thereto in any desired manner, is the depending arm 22 provided adjacent its lower end with an opening 23 to receive one end of a coiled spring 24, the opposite end of the coiled spring being secured to a pin 25, extending inwardly from the bracket or plate 6, as shown more particularly in Figs. 2, 3, 4, 5 and 7 of the drawings. Projecting horizontally from one face of the arm 22 is a pin or screw 26 to which is pivotally connected one end of a slidable member 27, a spacing sleeve 28 being received on the pin or screw 26 between the arm 22 and the end of the slidable member, as shown more particularly in Fig. 7 of the drawings.

The slidable member is formed with the elongated opening 29 in which operates the shank of a screw 30, threaded in an opening in the bracket or plate 6. The outer or upper end of the elongated opening 29 is enlarged as shown at 31 to receive the screw 30, as shown more particularly in Fig. 5 of the drawings when the slidable member is in its lowermost position. Formed on the free or outer end of the slidable member 27 is an enlarged finger-engaging portion shown at 32.

When the parts are in the position shown more particularly in Figs. 1, 2 and 3 of the drawings, and it is desired to lower the eraser disc 9 into contact with the paper around the platen, the operator engages the finger-engaging portion 32 and on pressing down upon the same slides the member 27 to swing the arm 22 rearwardly and place the coiled spring 24 under tension. When the slidable member is lowered the screw 30 will be received in the enlarged end 31 of the opening 29 and thereby hold the slidable member in its lowered position against the action of the coiled spring 24. When the arm 22 is swung rearwardly it rotates the hollow rod or sleeve 1' and swings the eraser disc downwardly into the position shown more particularly in Figs. 4 and 5 of the drawings and into contact with the paper around the typewriter platen. When in this lowered position the eraser disc 9 will be rotated, in the manner previously described, by rotating the knob 10 and the erasure will be made. When it is desired to raise the eraser disc into its original position the operator engages the finger under the finger-engaging portion 32 and by raising the same slightly disengages the screw 30 from the enlarged end 31 of the opening and then the coiled spring 24 will return the parts to their original positions.

From the above detailed description it will be noted that in the present application I have illustrated, described and will claim, novel supporting means for the eraser, more particularly novel brackets or members for supporting the rotatable shaft which carries the eraser, as well as novel means for rotating the said shaft to lower the eraser or eraser disc into contact with the paper around the platen or to raise the same from engagement therewith.

Having fully described my invention what I claim as new and desire to secure by Letters Patent is:

An attachment for supporting an eraser relative to a typewriter platen including brackets 55 extending vertically and parallel with end portions of the typewriter frame, channel members detachably connected to the brackets and adapted to receive bottom edge portions of the typewriter frame, channel members detachably connected to the brackets intermediate their ends and adapted to receive vertical edge portions of the typewriter frame, and adjustable members carried by the brackets and operable in openings of the channel members for detachably connecting the brackets to the typewriter frame.

GEORGE H. HUTAFF, JR.
